UNITED STATES PATENT OFFICE.

OVILA J. LARMORE, OF WAPPINGERS FALLS, NEW YORK.

POSITIVE TIMER FOR LOCK-STITCH SEWING-MACHINES.

1,325,020.

Specification of Letters Patent. Patented Dec. 16, 1919.

Application filed August 10, 1918. Serial No. 249,241.

To all whom it may concern:

Be it known that I, OVILA J. LARMORE, a citizen of the United States, residing at Wappingers Falls, in the county of Dutchess 5 and State of New York, have invented certain new and useful Improvements in Positive Timers for Lock-Stitch Sewing-Machines, of which the following is a specification.

10 This invention relates to those lock-stitch sewing machines employing an upper needle actuating shaft, a lower, loop-taker shaft, and a belt-drive connection between the said shafts.

15 The belt commonly used on such machines is either of leather, or, of hemp or cord strands and, after use for a relatively short period of time, stretches through use, or, by reason of oil thrown thereon when the 20 machine is in operation becomes unduly lengthened. This requires frequent removal and replacement of the belt used in this type of sewing machine, with incident loss of time of the operative and cost of upkeep.

25 Furthermore, looseness of the belt soon destroys the accurate timing of the loop-taker shaft with the needle actuating shaft, allowing the loop-taker to shake back and forth, instead of rotating in perfect timing 30 with the needle actuating shaft. As a result of looseness of the belt and this action of the loop-taker, stitches are skipped and threads are broken.

The well-known Willcox & Gibbs and 35 Singer sewing machines of the high-speed, lock-stitch type are subject to the foregoing troubles and it is the particular object of my invention to provide novel means which will insure accurate timing of the loop-taker 40 with the needle in such machines. The invention, however, is adapted for use in connection with any sewing machine having the two shafts aforesaid and a belt drive connecting them.

45 My object is to provide novel means, operating with the belt of a high-speed, lock-stitch sewing machine for the purpose of insuring positive timing of the upper and lower shafts and, hence, of the needle and 50 the loop-taker, to the end that broken threads, skipped stitches, and other defects due to looseness of the belt connecting said shafts, will be obviated, and the substitution of a new belt for one that has stretched 55 from any cause will be unnecessary. My invention not only saves time otherwise lost

in taking out a loose or stretched belt and putting in a new one but it enables a stretched belt to be used until worn out, thus saving expense.

60 The present invention requires no modification of the belt drive as now used on high-speed lock-stitch sewing machines but comprises novel means applicable to any machine of that class, adapted to take up 65 slack in the belt and to insure positive timing of the loop-taker shaft and the needle actuating shaft. The device is adapted for adjustment from time to time to compensate for further slack in the belt and enables 70 the belt to be used until it is worn out without necessitating removal of the belt from the sewing machine.

75 The embodiment of the invention herein-after described and which is disclosed in the accompanying drawings is subject to modification and is to be considered as illustrative, instead of restrictive, of the scope of the invention.

80 In the accompanying drawings:

Figure 1 is a side elevation, partly broken away, of a high-speed, lock-stitch sewing machine equipped with my invention;

Fig. 2, is a vertical section on the line 2—2, Fig. 1;

Fig. 3, is a bottom view of the right-hand end of the machine of Fig. 1;

Fig. 4, is a detail side elevation, partly in section, of the timer by itself;

Fig. 5, is a detail rear elevation thereof;

Fig. 6, is a detail bottom view thereof; and

Figs. 7 and 8 detail views showing how the timer may be applied to another kind of sewing machine drive belt.

95 In Figs. 1, 2, 3, the invention is shown applied to the well-known Willcox & Gibbs high-speed lock-stitch sewing machine, so much of the machine being illustrated as will disclose the nature of the invention; it 100 is to be understood, however, that the invention is applicable to any sewing machine having a belt drive between the upper needle-actuating shaft and the lower loop-taker shaft.

105 The bed-plate appears at 1, the arm at 2 and the hollow pillar at 3. The upper, needle-actuating shaft 4 drives the needle 5 and is provided with the usual pulley 6 and balance wheel 7. The lower shaft 8 is 110 journaled in suitable bearings below the bed-plate 1 and carries the usual loop-taker

9 which, in coöperation with the needle 5, forms the lock-stitch. The feed is operated by the rock-shafts 10, 11, which are operatively connected to the shaft 4 by connecting rods 12, 13.

Fast on shafts 4 and 8, respectively, are the sprockets or pin-wheels 14, 15 which are connected by an endless belt 16 having perforations 17 that receive the pins or teeth on the wheels 14, 15. The common practice is to use a light leather belt 16 and to reinforce the perforations 17 with metallic eyelets. The object of the direct belt-drive thus provided is to positively revolve the shaft 8 in perfect timing with the shaft 4 from which it is driven, thereby causing the loop-taker 9 to so perfectly coördinate with the needle 5 that a perfect lock-stitch will result.

20 In practice, however, such perfect timing does not result from this belt-drive. The belt stretches from use, which is greatly increased by its being subject to oil thrown thereon by the moving parts of the machine. Consequently, undue stretching of the belt 16 soon causes the holes 17 to now and then skip the pins of the wheels 14, 15, thus destroying the timing of the needle 5 and loop-taker 9, resulting in skipped 30 stitches and broken threads. A new belt must then be substituted for the one in use, which requires considerable time and involves the cost of the new belt and loss of the old one which is not worn out and yet 35 has to be discarded because its usefulness has ended.

To remedy the foregoing difficulty and expense, I have devised novel, adjustable means coöoperating with the belt 16 by which 40 slack therein is taken up and positive timing of the needle and loop-taker insured. The invention is shown detached in Figs. 4, 5, 6 and applied to the sewing machine in Figs. 1, 2, 3.

45 Referring first to Figs. 4, 5, 6, the base plate 18 is provided with holes 19 to receive machine screws 20 (Figs. 2, 3) for attaching the device to the underside of the bedplate 1. Suitably fastened to the base plate 18 is a hinge 21 to which, in turn, is fastened, as at 22, one part 23 of an angular arm 24 which has a screw-clamp 25 for adjustably securing one end of a pintle or stub-shaft 26 on which is journaled a roller 27. The 50 part 23 has a hole 28 through which loosely passes a tension screw 29 which has its end engaged with a screw-threaded hole 30 in base plate 18; a coil spring 31 surrounds the shank of screw 29 between the part 23 and the head of the screw and tends to force 55 the part 23 toward the base plate 18. Two screws 32, which engage screw-threaded

holes in the part 23, have their tips bearing on the base plate 18 at 33. These screws may be turned to adjust the arm 24, and hence the roller 27 as may be desired. The spring 31 keeps the tips of the screws 32 against the base plate 18 at all times but yields, or expands, as the case may be, when the screws 32 are adjusted.

70 The positive timer described is applied to the bed plate 1, and coöperates with the belt 16, in the manner shown in Figs. 1, 2, 3. The base plate 18 is so positioned, and secured by the machine screws 20, that the arm 24 extends up within the hollow pillar 3, the roller 27 bearing on one stretch of the belt 16. By suitably adjusting the screws 32 the roller 27 will bear with the proper pressure on the belt 16 to insure that 80 every perforation 17 receive a pin or tooth of the wheels 14, 15. Consequently, the lower shaft 8 will be rotated in perfect timing with the upper shaft 4 and the needle 5 will correctly coöperate with the loop-taker 9 to insure the formation of perfect lock-stitches at all times.

85 As the belt 16 stretches from use, the screws 32 may be quickly and easily turned by a screw driver without necessitating any other adjustment to compensate for the slack. The belt does not have to be removed, as has heretofore been necessary when the belt stretched and the timing was destroyed, and the effective life of the belt 95 is greatly increased.

The Singer machine employs a belt composed of parallel cords connected together by transverse clips as shown at 34, Figs. 7 and 8, for driving the lower shaft 8 from 100 the upper shaft 4. The belt runs over wheels 35, 36 which have notches or grooves 37 to receive the clips 34. My invention may be applied to this type of belt, so as to be used on the Singer machine, by substituting for the roller 27, a roller 38 having notches or grooves 39.

90 What I claim is:

A self-contained belt-tightener, adapted to be attached to a sewing machine for coöperating with the belt which connects the needle-actuating shaft and the loop-taker operating shaft to insure positive timing of the shafts aforesaid, comprising a base plate, an arm hinged thereto, a roller carried by the arm and adapted to bear on the belt, a screw threaded through the arm and having its tip bearing on the base plate, a screw engaged with the base plate and passing loosely through the arm, and a spring coöperating with said last-named screw and with the arm.

110 In testimony whereof I affix my signature.
OVILA J. LARMORE.
